UNITED STATES PATENT OFFICE.

WILLIAM ARTHUR BENNETT, OF LONDON, ENGLAND.

NECKTIE-FASTENER.

No. 829,053.

Specification of Letters Patent.

Patented Aug. 21, 1906.

Application filed August 1, 1905. Serial No. 272,161.

To all whom it may concern:

Be it known that I, WILLIAM ARTHUR BENNETT, a subject of the King of Great Britain, residing at London, in the county of Middlesex, England, have invented certain new and useful Improvements in Necktie-Fasteners, of which the following is a specification, such as will enable those skilled in the art to which it appertains to make and use the same.

This invention relates to means or devices for holding a necktie of any kind or class in proper position; and the invention consists of a particularly-formed shirt-stud designed for use in connection with a scarf or other pin.

The invention is fully disclosed in the following specification, of which the accompanying drawings form a part, in which the separate parts of my improvement are designated by suitable reference characters in each of the views, and in which—

Figure 1 is a perspective view of a part of a shirt-bosom and collar and showing my improvement applied for holding a four-in-hand or similar tie in place; Fig. 2, a front view showing my improvement applied for holding an ordinary bow-tie or string-tie in position; Fig. 3, a perspective view of one form of a shirt stud or button which I employ; Fig. 4, another view showing a modification of the shirt stud or button, and Fig. 5 a view of one form of a pin which is designed for use in connection with the form of stud or button shown in Fig. 4.

In the drawings forming part of this specification I have shown at *a*, Fig. 1, a part of a shirt-bosom, together with a collar *a*² and an ordinary four-in-hand tie *b*, and in Fig. 2 I have shown an ordinary standing collar *c* and a string tie made into a bow *d*.

In the practice of my invention I provide an ordinary shirt stud, button, or collar-button *e*, one form of which is shown in Fig. 3, and the head *e*² of this button is provided with a transverse bore or passage *e*³, and in the practice of my invention as shown in Fig. 1 the button *e* is used as an ordinary shirt-stud, and a scarf or other pin *f* is passed through the necktie or the bottom portion thereof and through the head of the stud *e*, as clearly indicated in dotted lines in Fig. 1. This, as will be understood, securely holds the tie *b* in proper place, and no ordinary movement will disconnect the pin from the stud,

and in practice the point of the pin after being passed through the stud is passed into the back portion of the lower part of the tie.

In Fig. 2 I have shown my improvement applied to an ordinary standing collar and an ordinary string tie, which is made into a bow *d*, and in this application of my invention the stud *e* is used as a collar-button, while an ordinary pin *g* is passed centrally and longitudinally through the middle portion of the bow *d* and through the head of the stud, as clearly indicated in dotted lines in said figure.

In the form of stud shown in Fig. 4 the opening *e*³ in the head *e*² thereof is provided with a plurality of V-shaped recesses *e*⁴, three of which are shown, and the pin *f*, (shown in Fig. 5,) which is used in connection with a stud made in this manner, is provided at its pointed end with a part *f*², which is similar in form in cross-section to the bore or passage *e*³ in the head *e*² of the stud, and when this form of pin is used the said pin must be held so as to permit of the passage of the point thereof through the head *e*², and the pin cannot be removed without properly adjusting the same in the operation of withdrawing it from the head of the stud, and this prevents the accidental withdrawal of the pin or the release thereof from said head of the stud.

It will be seen that the form of bore or passage *e*³ in the head *e*² of the stud or button shown in Fig. 4 is made irregular by means of the recesses *e*⁴, and when this form of stud or button is employed the bore or passage *e*³ may be made irregular in form in any desired way, and the end portion *f*² of the pin *f* (shown in Fig. 5) may be of any desired shape in cross-section corresponding to opening *e*³.

My invention is not limited to any particular form or style of stud, and the head of the stud may be made of any desired shape, all that is necessary in this connection being that the head of the stud shall have a transverse bore or passage sufficient to permit of the insertion therethrough of a pin, and it will also be apparent that any suitable form of pin may be employed.

I claim—

1. The herein-described necktie-holding device, comprising an ordinary collar button or stud and an ordinary scarf-pin, the button or stud being composed of a back portion and

a shank provided with a head, said head being provided with a transverse aperture through which the shank of the pin is adapted to be passed, substantially as shown and described.

2. The herein-described means for holding a necktie in position, comprising a shirt stud or button the head of which is provided with an irregular transverse bore, and a pin the pointed end portion of which is irregular in

cross-section, substantially as shown and described.

In testimony that I claim the foregoing as my invention I have signed my name, in presence of the subscribing witnesses, this 22d day ¹⁵ of July, 1905.

WILLIAM ARTHUR BENNETT.
